R. Deegan

Street Sweeper

No 11014.

Patented Jan 6, 1864.

UNITED STATES PATENT OFFICE.

ROSS DEEGAN, OF NEW YORK, N. Y.

IMPROVED MACHINE FOR CLEANING AND WATERING STREETS.

Specification forming part of Letters Patent No. 11,014, dated June 6, 1854.

To all whom it may concern:

Be it known that I, ROSS DEEGAN, of the city, county, and State of New York, have invented a new and useful Improvement in Machines for Cleaning and Watering Streets; and I do hereby declare that the following is a full, clear, and exact description of the construction and operation of the same, reference being had to the annexed drawings, forming part of this specification, in which—

Figure 1 is a vertical longitudinal section of the machine on line xx of Fig. 3. Fig. 2 is an elevation of fan-chamber side of the machine; Fig. 3, a rear elevation of the machine.

Similar letters in the several figures refer to the same parts of the machine.

The nature of my invention consists in depositing the dirt thrown up by the movement of a rotary sweeper in a chamber in the rear portion of the machine by means of a draft created by a revolving fan or blower, the sweeper and fan being operated through suitable gearing by the forward movement of the rear wheels of the machine, and also in using in connection with the fan and sweeper an apparatus for distributing water, forming by the combination a machine that effectually cleans and waters the streets and removes the dust without annoyance to the neighboring residents and passers-by.

To enable others skilled in the art to make and use my invention, I will proceed to describe its construction and operation.

The machine consists of a long box elevated upon wheels and capable of being drawn forward by animal power. Upon one of the sides of the box is secured a circular fan-chamber H, opening only into the channels I and I', the channel I' joining the fan-chamber at its upper portion, as shown in Figs. 2 and 3, and the channel I entering the outside of the chamber, as shown in the same figures.

Across the interior of the machine extend the partitions $v' w' x' y' z'$, dividing the box into the following chambers. The partitions $v' w' z'$, a portion of x' , with the front boarding u' , form a water-chamber, receiving its supply at the top and discharging its contents through an opening t' in one side of the tank into the pipe G, Fig. 2, which leads to a perforated distributing-cylinder F, as shown in Figs. 1 and 3. This opening t' is covered by

a slide-valve E, flat against the side of the tank and fastened to the lever R, which valve is removed from the opening t' at the will of the operator by the drawing up of the rod r' .

Beneath the partitions x' and v' and in rear of the partition w' the machine is open, and in this space is placed the rotary sweeper B, composed of the shaft P', with a series of brooms p' running the entire length of the shaft, which rests in bearings in the lower side pieces j' of the machine. In the front part of this open space is the inclined apron b, hung between the posts g' of the frame, so that its lower end which rests upon the ground may readily conform to inequalities or obstructions above the surface.

Projecting in front of the box is the chamber T, communicating with the open space above referred to by the opening between the partition v' and apron b, extending the whole width of the machine. This chamber is entirely closed on one side and has in the other an opening equal in size to the lower extremity of the channel I, which terminates against the side of said chamber T. There is also in the side of the chamber T a door P for the removal of stones which may be thrown up by the sweeper or drawn up by the draft of the fan.

The space above the partitions y' , z' , and a small portion of x' is open at top, while between x' , y' , and the back boarding i' is the chamber D, into which the outlet of the channel I' opens, the width of the channel I' being shown in Fig. 3. The remainder of the open top between y' and i' has over it a reticulated covering S, made sufficiently fine to admit of the escape of air and at the same time be impervious to dust. The extent of this covering across the machine is shown in Fig. 3, as well as the position of the outlet of the channel I'. In rear of the chamber D is the door X for removing the contents of the chamber.

On the rear wheels A are pulleys n' , around which and the pulleys W on each extremity of the shaft W run the belts x, giving motion to the said shaft W' as the rear wheels A revolve. In the middle of the shaft W' is the pulley S', around which and the pulley t on the shaft J runs the band Z, rotating that shaft, which in its turn gives motion to the fan-shaft C and sweeper-shaft P' by means

of the bands Z' and y , passed over the pulleys a' and r on the shaft J and the aforesaid shafts C and P' .

The lower portion of the machine is surrounded by a stout cloth m for preventing the sweeper from throwing the dust without the machine when it is in operation.

The operation of my improved machine for cleaning the streets is as follows: The forward movement of the wheels A will, through the bands $x y z z'$ and pulleys n', W, s', t, a' , and r , produce a rotation of the sweeper B and fan C in the directions indicated by arrows 1 and 2, the fan creating a strong suction-current from the chamber T through the passage I and an equally strong driving-current from the fan-chamber II through the channel I' leading to the chamber D . The revolution of the sweeper drives the dust upon the apron b in the direction of arrow 3 and within the influence of the suction from the fan, which draws the dust through the chamber T into the channel I , as shown by arrows 4 and 5. Issuing from the channel I the dust enters the fan-chamber II at its outer side and is ejected into the channel I' , as shown by arrow 7, through which it passes, as shown by arrow 8, and issues into the chamber D , as shown by arrow 9, Fig. 3, the finely-reticulated cover S permitting the escape of the air, while the dust remains in the chamber D , which when filled is emptied by the door X . If the rod r' be drawn, as indicated by arrow 10, the valve E will slide from the opening t' and the water with which the tank is filled will pass into the pipe G and thence to the perforated discharging-cylinder F , from which it issues in a multitude of jets in the usual manner and sprinkles the street after it has been cleaned by the sweeping arrangement.

Stones that may be thrown upon the apron b by the sweeper and drawn over its upper extremity by the suction of the fan will fall to the bottom of the chamber T and may be removed by the door P .

The arrangement of the details of the non-essential parts of my invention need not necessarily be as above described, as the most suitable arrangement can only be arrived at by experiment.

I do not claim the rotary brush or the apron, as such have been used before in machines of this character. Neither do I claim of itself the revolving fan or blower; but

What I do claim as my invention, and desire to secure by Letters Patent, is—

The method of removing dust from streets by means of a rotary sweeper beneath the machine, combined with a fan revolving at high speed in an external chamber, which is connected by passages I, I' with the chamber which first receives the dust and the chamber of deposit, as hereinbefore specified, by which arrangement the dust is driven within the action of the fan by the sweeper and is by suction drawn to the fan-chamber, whence it is driven to the chamber D and there deposited, the air passing out under strong pressure through the finer reticulations S in the cover of said chamber D .

In testimony whereof I have hereunto subscribed my name before two subscribing witnesses.

ROSS DEEGAN.
